UNITED STATES PATENT OFFICE

145,133

DESIGN FOR A PLACE MAT OR SIMILAR ARTICLE

Kenneth C. Hamilton, Milwaukee, Wis., assignor to Milwaukee Lace Paper Company, Milwaukee, Wis., a corporation of Wisconsin

Application March 27, 1946, Serial No. 127,987

Term of patent 14 years

(Cl. D59—2)

To all whom it may concern:

Be it known that I, Kenneth C. Hamilton, a citizen of the United States, residing at Milwaukee, in the county of Milwaukee and State of Wisconsin, have invented a new, original, and ornamental Design for a Place Mat or Similar Article, of which the following is a specification, reference being had to the accompanying drawing, forming part thereof, and in which the figure of the drawing is a face view of a place mat or similar article, embodying my new design.

I claim:

The ornamental design for a place mat or similar article, substantially as shown.

KENNETH C. HAMILTON.
